(57) **CLAIM**

The ornamental design for a flare gas assembly housing, as shown and described.

DESCRIPTION

FIG. 1 is a front elevational view of the flare gas assembly housing, the back elevational view being identical to the front elevational view;

FIG. 2 is a side elevational view thereof, the opposite side elevational view being a mirror image to that of FIG. 2;

FIG. 3 is a top plan view thereof;

FIG. 4 is a bottom plan view thereof, taken along the lines 4-4 of FIG. 1; and,

FIG. 5 is an isometric view thereof.

The broken lines shown in the drawings are included for the purpose of illustrating portions of the article that form no part of the claimed design.
